(57) **CLAIM**

The ornamental design for a vest with breathing apparatus, as shown and described.

DESCRIPTION

FIG. 1 is a perspective view of a vest with breathing apparatus in accordance with an embodiment of the invention;

FIG. 2 is a front view of FIG. 1;

FIG. 3 is a back view of FIG. 1;

FIG. 4 is a left view of FIG. 1;

FIG. 5 is a right view of FIG. 1;

FIG. 6 is a perspective view of the vest with the breathing apparatus having a cap;

FIG. 7 is a front view of FIG. 6;

FIG. 8 is a left view of FIG. 6; and,

FIG. 9 is a right view of FIG. 6.

The broken lines are for illustrative purposes only and form no part of the claimed design.

The broken lines showing in FIGS. 1, 2, 4, 5, 6, 7, 8, and 9 are understood to represent stitching.
